UNITED STATES PATENT OFFICE.

ARTHUR H. FARGO, OF WILMINGTON, DELAWARE, ASSIGNOR, BY MESNE ASSIGNMENTS,
TO CHARLES TREMAIN.

CONNECTING DEVICE.

1,220,326.

Specification of Letters Patent. Patented Mar. 27, 1917.

Application filed April 10, 1914. Serial No. 831,009.

To all whom it may concern:

Be it known that I, ARTHUR H. FARGO, a citizen of the United States, residing at Wilmington, in the county of Newcastle and State of Delaware, have invented new and useful Improvements in Connecting Devices, of which the following is a specification.

This invention relates to a connector for wires, cables, and the like, whether intended for use as conductors of electricity or not, the object being to provide a device of this character which will bind the end portions of the wires securely together and which, if they are electric conductors, will afford perfect electrical contact therebetween at all times.

A further object of the invention is to provide a connector which may be applied conveniently and quickly to the ends of the wires or cables, and which comprises a minimum number of parts so as to be durable and inexpensive in the cost of manufacture.

Broadly, the invention consists in the features of construction, combination, and arrangement of parts, hereinafter fully described and claimed, reference being made to the accompanying drawings, in which Figure 1 is a longitudinal sectional view through the preferred form of connector; Fig. 2 is an elevational view of the same; Fig. 3 is a detail perspective view of one of the gripping members; and Fig. 4 is a transverse sectional view on the line 4—4 of Fig. 2.

Referring to the drawings, the preferred form of connector comprises two terminal members 1 and 2 and an intermediate washer 3, the latter being made of rubber, fiber or metal, as may be desired. The terminal members are shown as being substantially frusto-conical in shape and hollow, their inner ends being respectively internally and externally threaded for the purpose of connecting them together, and enlarged to provide heads having polygonal outer surfaces 4 for the application of wrenches thereto.

The said terminal members afford outwardly tapering plug sockets 5 which are in communication with openings 6 provided in the end walls thereof, the latter being intended for the insertion of the ends of the respective wires 7 to be connected. Plugs 8, which are shown in detail in Fig. 3, are adapted to be mounted within the socket of

each terminal member with their larger ends disposed innermost and abutting against each other.

The inner ends of the said plugs are preferably tapered for a short distance while their outer ends are tapered oppositely for a greater distance. Each plug is provided with a longitudinal bore 9 and has its outer tapered portion slotted longitudinally, to provide yielding gripping portions or jaws 10 for engagement with the wire passing between them.

In this device, the larger ends of the gripping plugs are adapted to abut against each other, and consequently, when the companion members are adjusted, the meeting ends of the two plugs will engage each other frictionally, as they are rotated by their respective terminal members, the plug sockets in the said last-named members and the plugs being correspondingly substantially elliptical in transverse section as shown particularly in Fig. 4. It is to be understood, however, that the said sockets and plugs may be constructed circular in cross section if that should prove to be more desirable.

A secure mechanical joint will be provided by this connector between two wires and, if the device is used for connecting electrical conductors, a joint of perfect electrical conductivity will also be provided, as indicated by the absence of a rise in temperature of the respective parts due to the resistance characteristic of poor contacts. Also, from the foregoing description, taken in conjunction with the accompanying drawings, it is apparent that a connector for the meeting ends of electrical conductors has been provided, wherein novel and valuable details of construction have been employed.

What is claimed is:

1. A connecting device, comprising members having sockets therein, said sockets being tapered and having their larger ends disposed adjacent to each other, a plurality of tapered plugs adapted to surround the adjacent portions of a plurality of wires and to coöperate with the surfaces of the respective sockets of said members with their larger ends abutting each other, and means whereby said members may be adjusted relatively.

2. A connecting device comprising a body including companion members having alining sockets therein, the said sockets being

tapered and having their larger ends disposed adjacent to each other, a pair of tapered plugs adapted to be connected with the adjacent ends of a plurality of wires 5 and to be mounted within and coöperate with the walls of the respective sockets of the body members with their larger ends abutting each other, the said members being provided in their outer ends with openings 10 receiving the said wires, the inner end of one body member being externally threaded, and an internally threaded flange formed upon the inner end of the opposite member for engagement with the threaded portion 15 of the first member.

3. A connecting device comprising a body including companion members having alining sockets therein, the said sockets being tapered and having their larger ends disposed adjacent to each other, a pair of tapered plugs adapted to be connected with the adjacent ends of a plurality of wires and to be mounted within the respective sockets of the body members with their larger ends 20 abutting each other, the said members being provided in their outer ends with openings receiving the said wires, the inner end of one body member being externally threaded, an internally threaded flange formed upon 25 the inner end of the opposite member for engagement with the threaded portion of the first member, and means for securing each plug against rotation within the receiving socket.

35 4. A connecting device comprising a body including companion members having alining sockets therein, the said sockets being tapered and having their larger ends disposed adjacent to each other, a pair of tapered plugs adapted to be connected with the adjacent ends of a plurality of wires and to be mounted within the respective sockets of the body members with their larger ends abutting each other, the said members being provided in their outer ends with openings 40 receiving the said wires, the inner end of one body member being externally threaded, and an internally threaded flange formed upon 45 the inner end of the opposite member for engagement with the threaded portion of the first member.

50

portion of the first member, each plug and the receiving socket being elliptical in transverse section.

5. A connecting device, comprising members having tapered sockets therein, a plurality of tapered plugs respectively adapted to surround the adjacent portions of a like number of bodies and to be mounted within and coöperating with the surfaces of the respective sockets of said members with their larger ends abutting each other, and means by which said members may be adjusted relatively. 55

6. A connecting device, comprising members having tapered sockets therein, a plurality of tapered plugs respectively adapted to surround the adjacent portions of a like number of bodies and to be mounted within and coöperating with the walls of the respective sockets of said members with their 60 larger ends abutting each other, and said members being respectively externally and internally threaded to adjustably secure the same together. 65

7. A connecting device, comprising members having tapered sockets therein, a like number of tapered plugs respectively adapted to surround the adjacent portions of a plurality of bodies and to be mounted within the respective sockets of said members with their larger ends abutting each other, and means to prevent the circumferential movement of said plugs within 70 said sockets. 75

8. A connecting device, comprising members having tapered sockets therein, a like number of tapered plugs respectively adapted to surround the adjacent portions of a plurality of bodies and to be mounted within the respective sockets of said members with their larger ends abutting each other, and means to control or guide the 80 movement of said plugs within said sockets. 85

In testimony whereof I affix my signature in presence of two witnesses.

ARTHUR H. FARGO.
